UNITED STATES PATENT OFFICE.

JOHN F. KUHLMAN, OF HAMMOND, INDIANA.

SEWER-CLEANING APPARATUS.

1,185,686.

Specification of Letters Patent.

Patented June 6, 1916.

Application filed March 12, 1915. Serial No. 14,040.

To all whom it may concern:

Be it known that I, JOHN F. KUHLMAN, a citizen of the United States, and a resident of Hammond, in the county of Lake 5 and State of Indiana, have invented certain new and useful Improvements in Sewer-Cleaning Apparatus, of which the following is a specification.

My present invention relates to sewer 10 cleaning apparatus, and more particularly to the type in which a scraper is dragged to and fro between two successive manholes and withdrawn as often as the scraper bucket has been filled.

15 The principal objects of my present invention are to provide means whereby the end of the scraper proper acts as a scraper during the scraping operation, and as a bucket closing member during the reverse movement of the scraper; to provide means whereby the material removed from the sewer may be discharged from the scraper with a maximum of ease; to provide a scraper which will operate when lying on 20 its top as well as on its bottom side; to provide an improved scraper which can be put into operation without previous adjustment, together with certain further objects which will hereinafter appear.

25 In attaining the desired objects and certain additional advantages to be below pointed out, I have provided a construction, a preferred embodiment of which employing the present invention is illustrated in the 30 accompanying drawings wherein,—

Figure 1 is a vertical section through a manhole and portion of a sewer showing the apparatus in operative position, the discharging position of the bucket being shown 35 in dotted lines; Fig. 2 is a medial longitudinal vertical section of the bucket when in the scraping position; Fig. 3 is a top plan view of the bucket in the position shown in Fig. 2; and Fig. 4 is a section through the bucket on the line 4—4 of Fig. 2, viewed in the direction of the arrows.

Referring to Fig. 1 of the drawings, 1 represents the manhole over which is arranged a truck 2 which carries the hoisting 40 drum 3, whereby the scraper is hauled along the sewer to the bottom of the manhole and subsequently raised through the latter. This hoisting drum 3 is rotated by a crank 4. The rope or cable 5 leading from the haul-

ing drum passes over the pulley or sheave 6, and from thence into the manhole.

One of the features of my co-pending application is the manner in which the cable 5 is prevented from becoming frayed by rubbing against the end of the sewer where 60 the latter makes junction with the manhole and in which the bucket is carried clear of the manhole walls. In the arrangement shown a sheave 7 is provided around which the cable 5 passes to the scraper bucket 8, 65 this sheave being rotatably mounted on a pivoted pulley jack or arm 9, adapted to swing about a pivot 10, which may be suitably mounted on a frame temporarily fixed between the walls of the manhole. While 70 the scraper is being drawn along the sewer, the pressure of the cable against the pulley 7 keeps the arm 9 in its lowermost position. When, however, the scraper comes into contact with the sheave 7, or with the arm 9 75 carrying it, the latter is swung into the middle of the manhole thereby carrying the scraper proper clear of the manhole walls. Eventually, as the arm is raised, it is brought into the position shown in the dotted lines in Fig. 1, when a latch 11 engages a projection 12 on the arm 9, and holds the arm in its elevated position.

The cable 5 is free to leave the sheave 7 as soon as the tension on the cable tends to draw the cable away from the sheave. Accordingly, as soon as the arm 9 is brought to its elevated position shown in Fig. 1, the scraper 8 is free to rise unobstructed for the purpose of discharging its accumulated contents. The scraper is drawn upward by the cable 5 until it contacts with the pulley 6 when the chain 41 is swung across and the hook attached thereto brought into engagement with the part 40. Thereupon the cable 5 is released allowing the scraper to swing across to the position shown in dotted lines. The weight of the scraper then causes the ends of the scraper to open, as will be described later. After the scraper has been discharged and is returned to the manhole again for a further scraping operation, it is necessary, of course, to bring the sheave 7 once more into engagement with the cable 5. For this purpose the arm 9 is provided at its outer end with two diverging projections 13, so that when the arm 9 is released by lifting the latch 11, as by means of the

rope 14, these forked projections 13 will engage the cable 5 and guide the same into the groove of the sheave 7, whereupon the apparatus will resume a position for further 5 scraping.

While the sheave 7 provides for the passage of the cable 5 around the corner of the sewer during the scraping and hauling operations, it is also desirable to provide anti-friction rollers 15 suitably arranged on the frame which carries the pivoted pulley jack 9 for the cable 5 to pass over after the arm 9 has been raised to its elevated position.

The construction adopted for supporting 15 the arm 9 and its associated parts in the manhole 1 of the sewer is fully described in my co-pending application, Serial Number 855,656, and as it forms no part of the invention claimed in this application, its description 20 will be omitted here.

The scraper, as shown, is constructed so that one of the portions at one end acts as a scraper when the scraper is moved as a whole in scraping direction, and both end 25 portions act as closing members when the scraper is moved in the opposite direction. To accomplish this function the scraper is formed with two hemi-spherical shells or bucket portions 25 and 26 which are pivoted 30 to each other on each side at the point 27. These shells 25 and 26 are provided with runners or strengthening ribs 28 on their outsides. These ribs have hooked ends 29 which pass through holes in the end members 35 30 and 31, which end members are pivotally attached to side members 32 by the pins 33. The side members 32 have attached to each end the yokes 34 and 35, respectively to which the hauling cables are fastened.

It will be observed that the hemi-spherical bucket portions 25 and 26 are not connected to the cables used for drawing the scraper to and fro along the sewer except indirectly 45 by the hooked ends 29 of the ribs 28. Accordingly when the yoke 34 is pulled in the direction of the arrow in Fig. 2, the friction of the shell 25 against the bottom of the sewer causes the shell, by means of its hook 50 29, to pull the end portion 30 into its open or scraping position and simultaneously raise the upper portion 31, as shown in Fig. 2.

The extent to which the end portions 30 55 and 31 can open is limited by the projections 42 on the upper shell 26, which projections act as stops for the pins or projections 38 at the ends of the yoke 35, and which pass through the side bars 32. When the scraper 60 has been filled it is pulled in the opposite direction by means of the yoke 35. The first action of such movement is to move the side plates 32 so as to close the end of the scraper by bringing the parts 30 and 31 together.

65 The bucket portions of the scraper are

prevented from swinging transversely with respect to the side bars 32 during this relative motion of the bucket portions and the side bars 32 by shaping the adjacent edges 36 and 37 of the bucket shells so as to form 70 a slot in which the pin 38 can move to and fro as required.

I claim as my invention:—

1. A sewer scraper comprising in combination, side members, upper and lower end members pivoted thereto, upper and lower bucket members pivoted to the upper and lower parts of the corresponding end members and movable longitudinally relatively to said side members, said side members being pivotally attached to the lower and upper portions of said upper and lower end members respectively, and means for connecting said side members to the hauling means whereby one of the end members acts 85 as a scraper when the bucket is hauled in one direction and both end members act as closing members when the bucket is hauled in the opposite direction.

2. A sewer scraper comprising in combination, a bucket member, ribs on the under side of said bucket member, an end member pivotally attached at its lower portion to the bucket member by hooked ends on said ribs, hauling means connected to its upper portion whereby the end member acts as a scraper when the bucket is hauled in one direction and as a closing member when hauled in the opposite direction, and means for suspending the scraper attached to the 100 bucket member to allow the end member to fall in order to discharge the contents of the scraper therefrom.

3. A sewer scraper comprising in combination, side members, upper and lower end members pivotally attached thereto at their under and upper portions respectively, upper and lower bucket members, ribs on said bucket members, hooked ends on said ribs adapted to engage the upper and lower parts 110 of the corresponding upper and lower end members, and means for connecting said side members to the hauling means whereby one of the end members acts as a scraper when the bucket is hauled in one direction 115 and both end members act as closing members when the bucket is hauled in the opposite direction.

4. A sewer scraper comprising in combination, side members, a bucket member movable longitudinally relatively to said side members, an end member pivotally attached at its lower portion to the bucket member and at its upper portion to said side members, hauling means connected to the said side portions whereby said end portion acts as a scraper when the bucket is hauled in one direction and as a closing member when hauled in the opposite direction, and a stop 125 on the bucket member adapted to engage the 130

said hauling means and limit the opening of the end members.

5. A sewer scraper comprising, in combination, a bucket member, upper and lower 15
5 end members pivotally attached at their upper and lower portions respectively to the bucket member, a member connected to the lower portion of said upper end member, and to the upper portion of said lower end
10 member, and hauling means connected to said member whereby the lower end mem-

ber acts as a scraper when hauled in one direction, and both upper and lower end members act as closing members when hauled in the opposite direction.

In testimony whereof I have hereunto signed my name in the presence of the two subscribed witnesses.

JOHN F. KUHLMAN.
